M. MARTIN.

METHOD OF MAKING VASES.

APPLICATION FILED SEPT. 18, 1919.

1,353,928.

Patented Sept. 28, 1920.

Inventor

Max Martin

By his Attorneys

Edgar Foster Co.

UNITED STATES PATENT OFFICE.

MAX MARTIN, OF NEW YORK, N. Y.

METHOD OF MAKING VASES.

1,353,928.

Specification of Letters Patent. Patented Sept. 28, 1920.

Application filed September 18, 1919. Serial No. 324,364.

To all whom it may concern:

Be it known that I, MAX MARTIN, a citizen of the United States, and residing at New York, in the county of Bronx and State of New York, have invented certain new and useful Improvements in Methods of Making Vases, of which the following is a specification, such as will enable those skilled in the art to which it appertains to make and use the same.

This invention relates to the manufacture or making of vases and particularly to devices of this class designed for outdoor use, or for use in large buildings of any kind 15 or class, and the invention consists in an improved method of making articles of the class specified, whereby such articles are formed from reinforced cement or concrete, waterproof material and brick, and whereby 20 such articles may be made strong and durable and at a comparatively small cost and of any desired shape or configuration.

The invention is fully disclosed in the following specification, of which the accompanying drawing forms a part, in which the separate parts of my improvement are designated by suitable reference characters in each of the views and in which:—

Figure 1 is a semi-sectional side view of 30 a vase made according to my invention; and, Fig. 2 is a cross section thereof on the line 2—2 of Fig. 1.

In the practice of my invention I provide a central core *a* made of wood and consisting of separate detachably connected parts indicated by dotted lines in Figs. 1 and 2, and the form or shape of said core will determine, as will be understood, the form or shape of the vase.

40 I also provide a wire mesh jacket or casing *b*, which is of the same form as the core *a* but which is of greater dimensions than said core, whereby a space *c* is formed between the wire mesh jacket or casing *b* and the core, said space being of predetermined dimensions, and the core and wire mesh casing, the latter being preferably of what is known as one-half inch mesh, are so spaced one within the other, this operation being 45 performed by any desired means or in any preferred way, that the transverse dimensions of the space *c* may be regulated to any desired extent according to the size or dimensions of the vase which it is desired 55 to make.

The next step in the process consists in

filling the space *c* with cement or concrete, this operation being performed by working said cement or concrete through the jacket or casing *b* with a trowel or in any other 60 suitable way until said space is entirely filled with the cement or concrete, after which more cement or concrete is applied until the jacket or casing *b* is entirely covered and inclosed thereby as shown in the 65 drawing, and this method of procedure forms an inner body or base for the vase, which is composed of reinforced concrete or cement, the reinforcement consisting of the wire mesh jacket or casing *b* which is en- 70 tirely inclosed therein.

The next step in the process consists in covering the said reinforced body with waterproof material *d* of any suitable kind, and this waterproof material may form the 75 bottom of the vase, or the central part thereof as shown in Fig. 1; and after the main inner body portion of reinforced concrete has been covered by the waterproof material, the entire vase is inclosed or provided 80 with a finishing outer wall *e*, consisting of terra cotta or other bricks built up from the bottom as clearly shown in Fig. 1, and as indicated in Fig. 2, the best kind of cement being used in this operation, and as will be 85 understood, the outer wall *e* of the vase may be composed of bricks of any desired shape or form, or said outer wall may consist of inlay work of any kind or class.

It will be understood, of course, that vases 90 of any desired size, shape or form may be made in this manner, and said vases may be made as strong and durable as necessary or desirable, and in the process of forming the vase herein described the jacket or casing *b* may first be provided and the core *a* placed therein, or said core may first be built up and the jacket or casing *b* placed therearound in any desired manner; and changes in and modifications of the details 100 of the process herein described may be made, within the scope of the appended claims, without departing from the spirit of my invention or sacrificing its advantages.

Having fully described my invention, what 105 I claim as new and desire to secure by Letters Patent, is:—

1. The process herein described of making vases which consists in providing a central core of wood consisting of separate detachably connected parts, providing a wire mesh 110 jacket or casing in which said core is in-

closed, said jacket or casing being of greater dimensions than said core and said parts being so placed as to form a continuous space between them, then filling in said space with plastic cement worked through the wire mesh jacket or casing and entirely inclosing said wire mesh jacket or casing in said cement, then applying waterproof material to the reinforced cement body thus formed, then inclosing said body and the waterproof material in an outer wall consisting of brick or inlay work, and then removing said core.

2. The process herein described of manufacturing vases and the like which consists in providing a suitable core, inclosing said core in a jacket of openwork material which is spaced from said core, then applying ce-

ment to said core and said jacket to fill the space between said jacket and core and to embed the jacket in said cement, then applying a coating of waterproof material to the structure thus formed, then inclosing said structure with the waterproof material thereon in a brick construction to form a complete vase and then removing said core from the vase thus formed.

In testimony that I claim the foregoing as my invention I have signed my name in presence of the subscribing witnesses this 16th day of September, 1919.

MAX MARTIN.
